UNITED STATES PATENT OFFICE

168,546

MAGNIFIER AND ILLUMINATOR FOR VIEWING PRINTED MATERIAL AND THE LIKE

Emmerich T. Igler, New York, N. Y., and Raymond H. Wadsworth, South Orange, N. J.

Application August 14, 1952, Serial No. 21,042

Term of patent 7 years

(Cl. D57—7)

To all whom it may concern:

Be it known that we, Emmerich T. Igler, a citizen of the United States, residing at New York, county of New York, State of New York; and Raymond H. Wadsworth, a citizen of the United States, residing at South Orange, county of Essex, State of New Jersey, have invented a new, original, and ornamental Design for Magnifier and Illuminator for Viewing Printed Material and the like, of which the following is a specification, reference being had to the accompanying drawing, forming part thereof.

Fig. 1 is a top plan view of a magnifier and illuminator for viewing printed material and the like embodying our new design;

Fig. 2 is a side elevation thereof; and

Fig. 3 is an end elevation thereof as viewed from the left of Fig. 2.

We claim:

The ornamental design for a magnifier and

illuminator for viewing printed material and the like, substantially as shown.

EMMERICH T. IGLER.

RAYMOND H. WADSWORTH.
